The ornamental design for a light emitting diode (side view type), as shown and described.

DESCRIPTION

FIG. 1 shows a front view of the design according to a first embodiment of the invention.

FIG. 2 shows a rear view of the design according to the first embodiment of the invention.

FIG. 3 shows a top view of the design according to the first embodiment of the invention.

FIG. 4 shows a bottom view of the design according to the first embodiment of the invention.

FIG. 5 shows a left side view of the design according to the first embodiment of the invention. The right side view is a mirror image of the left side view.

FIG. 6 shows a top perspective view of the design according to the first embodiment of the invention.

FIG. 7 shows a bottom perspective view of the design according to the first embodiment of the invention.

FIG. 8 shows a front view of the design according to the first embodiment of the invention, indicating a translucent portion.

FIG. 9 shows a front view of the design according to a second embodiment of the invention.

FIG. 10 shows a rear view of the design according to the second embodiment of the invention.

FIG. 11 shows a top view of the design according to the second embodiment of the invention.

FIG. 12 shows a bottom view of the design according to the second embodiment of the invention.

FIG. 13 shows a left side view of the design according to the second embodiment of the invention. The right side view is a mirror image of the left side view.

FIG. 14 shows a top perspective view of the design according to the second embodiment of the invention.

FIG. 15 shows a bottom perspective view of the design according to the second embodiment of the invention; and, FIG. 16 shows a front view of the design according to the second embodiment of the invention, indicating a translucent portion.

The elements shown in broken lines are for illustrative purposes only and form no part of the claimed design.
